UNITED STATES PATENT OFFICE.

JOHN C. WANDS, OF ST. LOUIS, MISSOURI.

FLUID SPEED-GOVERNING CLUTCH.

No. 836,348.

Specification of Letters Patent.

Patented Nov. 20, 1906.

Application filed May 21, 1906. Serial No. 317,946.

To all whom it may concern:

Be it known that I, JOHN C. WANDS, a citizen of the United States, residing at St. Louis, Missouri, have invented a certain new and useful Improvement in Fluid Speed-Governing Clutches, of which the following is a full, clear, and exact description, such as will enable others skilled in the art to which it appertains to make and use the same, reference being had to the accompanying drawings, forming part of this specification, in which—

Figure 1 is a longitudinal sectional view through a fluid speed-governing clutch embodying the features of my invention; Fig. 2 is a sectional view taken on the line 2-2 of Fig. 1. Fig. 3 is an end view looking from the right-hand side of Fig. 1. Fig. 4 is a detail view, partly in section, of the skeleton-like sleeve on which the piston is mounted; and Fig. 5 is an end view showing a pulley connected to the cylinder in which the piston is mounted.

This invention relates to fluid speed-governing clutches adapted to be arranged between driving and driven members for controlling the speed of the driven member; and the object of my invention is to provide a clutch of the character referred to, which is of simple construction. The driving member has a piston connected thereto in such manner that said piston is capable of reciprocating longitudinally of said driving member, such reciprocating movement resulting from the rotary movement of said driving member. The cylinder or casing in which the piston is mounted is filled with fluid, preferably oil, and is connected to the driven member, and means is provided for regulating the passage of the fluid to and from the opposite sides of the piston through suitable by-passes. Thus if the by-passes for the fluid are closed or choked the piston will not move freely in its cylinder, and consequently the rotary motion of the driving member will be communicated to the driven member to which the cylinder-casing is attached, said casing being provided with inwardly-disposed projections which coöperate with a cam on the piston. The relative speed of the driven member is proportionate to the freedom of movement of the piston. When the by-passes are entirely closed, the fluid cannot escape from the front side of the

piston, and consequently the piston cannot reciprocate, so that the driven member will be positively connected to the driving member and will be rotated at the same speed. When the by-passes are fully opened, the driven member, if it has a load imposed thereon, will remain stationary while the driving member is rotating at full speed, due to the fact that the fluid can escape from the front side of the piston to the rear side thereof through said by-passes.

Referring to the drawings, which represent the preferred form of my invention, I designate the driving member, herein shown as a shaft which receives motion from any suitable source of power, and 2 is the driven member, also shown as a shaft. A sleeve 3 is mounted on the end of the shaft 1, said sleeve having inwardly-projecting arms 4, which engage the shaft 1, keys 5 being provided for rigidly connecting said sleeve and shaft together. A piston 6, provided with a cam 7, is mounted on this sleeve, and a key 8 is provided for connecting the piston to the sleeve, whereby said piston is adapted to move longitudinally thereof. The extreme end of the driving-shaft extends into a recess formed in a head-casting 9, provided with a sleeve 10, to which the driven shaft 2 is connected by means of a pin 11. The cylinder in which the piston operates is connected to the head-casting 8 by means of screw-threads and also rivets 13, as shown in Fig. 3, the opposite end of said cylinder being mounted on the driving-shaft 1 and being provided with a stuffing-box 14, through which said shaft extends. Rigid projections or pins 15 extend inwardly from the cylinder and coöperate with the cam 7, formed on the piston, the cylinder being filled with some fluid, preferably oil. The sleeve 3 is provided at its opposite ends with ports 16 and 17, and the spaces between the inwardly-extending arms 4 of said sleeve form by-passes through which the fluid can flow as it is displaced by the reciprocation of the piston in the cylinder. The valve 18, which may be in the form of a ring, surrounds the sleeve 3 and controls the passage of the fluid through the ports 17, said valve being reciprocated longitudinally of the sleeve 3 by any suitable means. I have herein shown said valve 18 as being carried by pins 19, project-

ing from a grooved collar 20, which may be positively actuated by a lever or similar device, said pins extending through stuffing-boxes 21 in the head-casting 9.

5 In operation if the driven shaft 2 is loaded and the ports 17 in the sleeve 3 are fully opened it will be obvious that the rotation of the driving-shaft will cause the piston to reciprocate in its cylinder and force the liquid 10 from the front of the piston through said ports to the by-passes on the interior of the sleeve and through the ports 16 into the cylinder at the rear of the piston. If the collar 18 is moved to partially close the ports 17, 15 the resistance offered to the flow of liquid through said ports will be transmitted to the shaft 2, and consequently said shaft will be driven, though perhaps at a low speed. If the collar 18 is moved to entirely close the 20 ports 17, it will be impossible for the liquid to escape from the front of the piston, and consequently the driven shaft will be locked to the driving-shaft and will be rotated at the same speed. The gradual opening of the 25 ports 17 will remove the restrictions upon the flow of the liquid from one end of the piston-cylinder to the other and will permit said piston to reciprocate slightly on shaft 1, which results in a corresponding loss of speed 30 in shaft 2, this continuing until the valve-collar 18 is fully opened, when if shaft 2 is carrying a load sufficient to overcome the friction of the piston in its cylinder said shaft will be brought to rest while shaft 1 continues to rotate, the piston reciprocating 35 idly back and forth in the cylinder.

In Fig. 5 I have shown the cylinder 12 as having the arms 22 of a pulley 23 cast integral therewith, or, if desired, the hub of a 40 pulley could be connected to the cylinder. While I have shown the sleeve 3 as being formed separate from the shaft 1 and being connected thereto by keys, it should be understood that these parts could be made 45 integral without departing from the spirit or scope of my invention.

Having thus described my invention, what I claim as new, and desire to secure by Letters Patent, is—

50 1. The combination with a driving member and a driven member, of a piston mounted on the driving member and adapted to reciprocate longitudinally thereof, a piston-cylinder connected to the driven member and adapted to receive a fluid, means for reciprocating said piston, a by-pass arranged adjacent the axis of the piston to provide a passage from one side of the piston to its other side, and means for regulating the flow of liquid through said by-pass; substantially as described.

2. The combination with a driving mem-

ber and a driven member, of a piston mounted on the driving member and adapted to reciprocate longitudinally thereof, a piston-cylinder connected to the driving member and adapted to receive a fluid, a rigid member projecting inwardly from said cylinder and coöperating with an irregular surface on the piston, a by-pass arranged adjacent the axis of the piston to provide a passage from one side of the piston to its other side, and means for regulating the flow of liquid through said by-pass; substantially as described.

3. The combination with a driving member and a driven member, of a piston mounted on the driving member and adapted to reciprocate longitudinally thereof, a cam on said piston, a piston-cylinder connected to the driven member, and adapted to receive a fluid, rigid projections extending inwardly from the cylinder and coöperating with the cam on the piston, a by-pass arranged adjacent the axis of the piston to provide a passage-way from one end of the cylinder to the other end thereof, and means for regulating the flow of liquid through said by-pass; substantially as described.

4. The combination with a driving member and a driven member, a sleeve on the driving member having a by-pass formed on the interior thereof, ports in the outer face of said sleeve arranged at the ends of said by-pass, a piston reciprocatingly mounted on said sleeve, a cylinder connected to the driven member and adapted to receive a fluid, an inwardly-extending projection on said cylinder coöperating with an irregular surface on the piston, and means for regulating the flow of liquid through said by-pass; substantially as described.

5. The combination with a driving member and a driven member, a sleeve on the driving member having a by-pass formed on the interior thereof, ports in the outer face of said sleeve arranged at the ends of said by-pass, a piston reciprocatingly mounted on said sleeve, a cylinder connected to the driven member and adapted to receive a fluid, an inwardly-extending projection on said cylinder coöperating with an irregular surface on the piston, and a collar reciprocatingly mounted on said sleeve for closing one of the ports therein to regulate the flow of liquid through said by-pass; substantially as described.

6. The combination with a driving member and a driven member, a sleeve carried by said driving member and provided with a plurality of longitudinally-extending spaces arranged inside said sleeve, ports formed in the outer surface of said sleeve at the opposite ends of said spaces, a piston reciprocatingly mounted on said sleeve and provided

with a cam, a piston-cylinder connected to the driven member and adapted to contain a fluid, and a valve for closing the ports at one end of said sleeve for regulating the flow of liquid through the spaces on the interior of the sleeve; substantially as described.

5 In testimony whereof I hereunto affix my

signature, in the presence of two witnesses, this 19th day of May, 1906.

JOHN C. WANDS.
